UNITED STATES PATENT OFFICE.

WALTER R. NOE, OF NEW YORK, N. Y.

PENCIL.

1,427,409.

Specification of Letters Patent. Patented Aug. 29, 1922.

Application filed May 10, 1920. Serial No. 380,021.

To all whom it may concern:

Be it known that I, WALTER R. NOE, a citizen of the United States, and a resident of the borough and county of the Bronx, city 5 and State of New York, have invented certain new and useful Improvements in Pencils, of which the following is a specification.

My invention relates to mechanical pencils and has for its object to provide a construction of extreme simplicity with a minimum of parts and of relatively low cost and which includes a storage space for spare leads. The invention will be fully described 15 hereinafter and the features of novelty will be pointed out in the appended claim.

In the accompanying drawings, which illustrate an example of my invention, Fig. 1 is a longitudinal section of the pencil; Fig. 20 2 is a view of the barrel; Fig. 3 is a perspective view of a plug which may form part of the pencil; Fig. 4 is a cross-section on the line 4-4 of Fig. 1; Fig. 5 is a detail view of the cap and its corelated parts and Fig. 25 6 is a view illustrating the interior tube included in my pencil.

As shown in the illustrated example, the pencil comprises a tubular barrel 10 of suitable material and formed with a tapering 30 axis end 11, said barrel itself preferably having a uniformly smooth exterior surface. A tube 12 extends lengthwise of the barrel 10 and has its inner end secured internally thereof at the apex of the exit end 35 11 of said barrel 10 and is preferably split or quartered to frictionally hold the lead 13 as it protrudes from said barrel. The tube 12 has its outer end internally screw-threaded at 14 and externally screw-threaded at 40 15, and at this end preferably projects somewhat beyond the barrel 10 and screws into a plug 16 which frictionally fits into said barrel to close the chamber 19 and at the same time to fix said tube rigidly in 45 position and properly center the same; the plug 16 is preferably formed with an annular shoulder 17 to limit its normal movement into the barrel 10. In order to still further increase the rigidity of the construction, a washer 18 may be placed upon the tube 12 within the barrel 10 and secured in 50 position either by friction or otherwise, it being understood that the diameter of said washer is such as to frictionally fit within said barrel and outside of said tube. In addition to its other functions said washer 18

may constitute the bottom of an annular chamber 19 which may be utilized as a storage space for spare leads 13. If desired, this washer 18 alone may be relied upon to 60 fix the tube 12 in position against vibration, in which case the plug 16 may be omitted.

The means whereby the lead 13 is selectively projected from the barrel 10 comprises a stem 20 which extends into the tube 65 12 and is of relatively smaller diameter so as to be freely movable lengthwise thereof without interference. The stem 20 comprises an integral extension of a rod 21 which is externally screw-threaded to screw into said tube 12 and which is secured within a cap 22 so as to extend lengthwise thereof as shown in Fig. 1, said cap 22 fitting over the barrel 10 and being movable lengthwise thereof.

In the operative condition of the pencil or, in other words, when it is loaded, the stem 20 engages a lead 13^a located behind and in axial alignment with the active lead 13 which is in use and the one end of which projects beyond the exit end 11 of the pencil 70 for writing purposes. As the active lead 13 is worn down it is gradually advanced by rotating the cap 22 in a direction to cause the rod 21 to screw into the tube 12; this brings about a forward movement of 75 the stem 20 in an axial direction and causes it to exert a push upon the lead 13^a which is communicated thereby to the active lead 13, the end of which is correspondingly projected from the exit end 11. During 80 this advancing of the active lead 13 the cap 22 moves along the barrel 10 and finds a bearing thereon whereby the operation is 85 efficiently carried out and vibration of the parts relatively to each other is avoided. 90 When one active lead 13 is consumed, it is preferred to advance the lead 13^a until its one end projects beyond the exit end of the tube 12 and to insert a new lead into said tube 12 after the rod 21 has been first completely unscrewed therefrom, it being understood 95 that this proceeding is optional and that a consumed lead may be replaced in any other way suitable to the present pencil.

It will be understood that in some cases 105 the stem 20 may be long enough to directly engage the active lead 13, thus doing away with the extra lead 13^a which is utilized as a pushing medium simply to maintain the parts of the cap within relatively small 110 limits.

The pencil is very simple in construction

and efficient in operation and is readily and easily maintained in a serviceable condition; because of its extremely simple construction and simplicity of operation the pencil is 5 economical to produce and is not easily disarranged. The provision of the washer 18 at the bottom of the chamber 19 in which spare leads are stored, prevents these spare leads from becoming wedged in the tapering 10 end 11 of the barrel 10.

Various changes in the specific form shown and described may be made within the scope of the claim without departing from the spirit of my invention.

15 I claim:

A pencil of the kind described comprising a barrel having a tapering exit end, a plug located in the inlet end of said barrel, an internally screw-threaded tube ex-

tending lengthwise of said barrel and having its exit end permanently fixed therein in registry with the exit end of said barrel, said tube having its inlet end held in said plug and being arranged to contain an active lead, a cap movably fitted upon said barrel 25 to complete the predetermined contour of said pencil, a screw-threaded rod fixed within and extending lengthwise of said cap and arranged to screw into said tube, and a stem 30 forming an axial extension of said rod and of smaller diameter than said tube, said stem being adapted to be moved lengthwise thereof, by the action of said rod, to advance the active lead in said tube.

In testimony whereof I have hereunto 35 set my hand.

WALTER R. NOE.
